FUSING LINK

Walter F. Kramer, Detroit, Mich.

Original application January 21, 1946, Serial No. 642,540. Divided and this application September 9, 1946, Serial No. 695,784

8 Claims. (Cl. 169—42)

1

This invention relates generally to fusing links and refers more particularly to improvements in fusing links of the type used in the automatic operation of fire extinguishers. This application is a division of my copending application Serial No. 642,540 filed January 21, 1946, now Patent No. 2,480,033, issued August 23, 1949.

Automatic fire control apparatus such as fire extinguishers are usually equipped with a fusing link or some equivalent element designed to automatically release a fire extinguishing fluid in gas or fluid form in response to a predetermined increase in the temperature of the atmosphere ambient to the apparatus. Thus, the effectiveness of the apparatus to extinguish or control fires depends to a great extent on the ability of the fusing link or similar device to initiate operation of the apparatus with a minimum delay after a fire is started.

With the above in view the present invention has as one of its principal objects to provide a fusing link which is highly sensitive to preselected abnormal temperatures and assures instantaneous operation of the apparatus to discharge fire extinguishing fluid when the atmosphere ambient to the fusing link reaches the preselected temperature.

Another object of this invention is to provide a fusing link composed of a relatively few simple parts capable of being inexpensively manufactured, assembled and installed.

The foregoing as well as other objects will be made more apparent as this description proceeds, especially when considered in connection with the accompanying drawing, wherein:

Figure 1 is a fragmentary longitudinal sectional view through a portion of a fire extinguisher showing my improved fusing link;

Figure 2 is a cross sectional view through the fire extinguisher shown in Figure 1;

Figure 3 is a cross sectional view taken on the plane indicated by the line 3—3 of Figure 1; and

Figure 4 is a detail elevational view of a part of the fusing link shown in Figure 3 and illustrating one method of making the fusing link.

For the purpose of illustrating this invention, I have selected a fire extinguisher of the type shown in my copending application, Serial No. 642,540 filed January 21, 1946, although it will be understood as this description proceeds that the fusing link featured herein may be advantageously employed to initiate the operation of other types of automatically operable fire control equipment. Briefly the fire extinguisher disclosed herein is adapted to be supported on the ceiling

2

of a room or other enclosure and is automatically operated by my improved fusing link in response to a predetermined temperature rise to discharge the contents of the extinguisher into the enclosure in the form of an enveloping fog. The fog is discharged under pressure, so that it rapidly displaces the oxygen around the fire and smothers the latter.

The fusing link is shown best in Figure 3 of the drawings and is indicated generally by the reference numeral 10. As shown in Figure 3 of the drawings the fusing link 10 comprises a ring 11 preferably formed of a non-metallic material such, for example, as fiber, rubber, synthetic rubber or some equivalent material and composed of two or more segments 12. The segments 12 are normally confined in a sectional band 13 and are urged outwardly by a segmental leaf spring 14 positioned in the ring 11 with the opposite ends respectively bearing on the inner surfaces of the ring segments. The sections of the band 13 are formed of a metal having a high thermal conductivity such, for example, as copper or similar metals, and are held together by a fusing metal having a melting point in a range of 140° F. to 240° F., for example. Any fusing metal having a sufficiently low melting temperature may be used and especially satisfactory results have been obtained with compositions produced by the "Cerro Bend Manufacturing Company" or by the "Belmont Smelting and Refining Company." The construction is such that the various sections of the band 13 are released from one another when the temperature ambient to the fusing link 10 approaches the melting point of the fusing metal employed to secure the sections together. When this condition exists, the leaf spring 14 forces the segments 12 of the ring 11 and the sections of the band 13 apart with an explosive action. Disintegration of the fusing link instantaneously releases the fire extinguishing fluid in a manner to be more fully herein-after described.

Before discussing the means for releasing the fire extinguishing fluid in response to disintegration of the fusing link, it is pointed out that the band 13 actually comprises eight sections indicated in the drawings by the reference character 15 and arranged in pairs. The sections of each pair are formed with arcuate portions 16 and with radially outwardly extending flanges 17. The arcuate portions 16 of one section overlap the arcuate portions of an adjacent section and are secured together by the fusing metal to form the band 13. The flanges 17 on the sections are

positioned in contact with each other and are arranged 90° apart as clearly shown in Figure 3 of the drawings. In operation the flanges 17 form fins which project a substantial distance into the atmosphere ambient to the fusing link and serve as heat conductors to facilitate the transfer of heat to the fusing metal. In the interests of economy in manufacture, each pair of sections are formed of one piece of sheet metal in the manner clearly shown in Figure 4 of the drawings and the return bent portion 18 connecting the extremities of the flanges 17 are sheared off to separate the sections.

It has previously been stated that the fusing link 10 is applied to a fire extinguisher of the type shown in my above identified copending application. This fire extinguisher comprises a container 10' and a discharge nozzle 11'. The container is in the form of an elongated tube sealed at opposite ends and adapted to contain a liquid having fire extinguishing characteristics such, for example, as carbon tetrachloride. The tube has an opening 12' intermediate the ends and a fitting 13' in the form of a casing or forging is brazed or otherwise secured to the tube in registration with the opening 12'. The fitting 13' is formed with an annular flange 14' internally threaded at the outer end for threadably receiving the nozzle 11'.

The nozzle 11' comprises a cap 26 threadably engageable with the annular flange 14' on the fitting 13' and having a central opening 27 registering with an outwardly extending tubular extension 28 of the cap. The extension 28 has a reduced portion 29 at the outer end thereof and is formed with a reduced tubular guide 30 intermediate the ends. The guide 30 is concentrically arranged with respect to the extension and the outer end of the guide is integrally connected to the extension at the inner side of the reduced portion 29 by an annular partition 31 having orifices 32 therethrough.

A plunger 33 is slidably supported in the guide 30 and is formed with a head 34 at the inner end positioned in the annular flange 14 adjacent the outer ends of cartridges 24. The cartridges 24 contain a suitable gas, such for example, as carbon dioxide under pressure, and are slidably supported within the container 10' by guides 16'. The guides 16' also provide supports for suitable punches 21 positioned to respectively pierce the inner ends of the cartridges 24 upon inward displacement of the latter relative to the guides. The plunger 33 projects outwardly beyond the outer end of the reduced portion 29 and a spray head 35 is slidably supported on the outer end of the plunger. The spray head has a sleeve portion 36 slidably mounted on the plunger in concentric relation to the reduced portion 29 and is formed with a frusto-conical surface 37 beyond the outer end of the reduced portion 29. The inside diameter of the reduced portion 29 is somewhat greater than the outside diameter of the sleeve portion 36 on the spray head and cooperates with the sleeve portion to form an annular passage 38 therebetween. The spray head 35 is removably held in assembled relation with the plunger 33 by a nut 39 threaded on the extreme outer end of the plunger 33.

The plunger 33 is normally in its outermost position shown in Figure 1 of the drawings wherein the head 34 engages the inner surface of the cap 26. A sealing gasket 40 is seated on the inner surface of the cap 26 around the

opening for abutting engagement with the head 34 on the plunger to seal the ports 32 from the container and thereby prevent leakage of the contents of the container.

The plunger 33 is normally urged to its innermost position shown in Figure 1 of the drawings by a coil spring 41 surrounding the plunger with the inner end abutting the head 34 and with the outer end abutting the annular wall 31. The spring is held under compression or, in other words, the plunger 33 is held in its outermost position shown in Figure 1 of the drawings by the fusing link 10. The fusing link 10 is positioned with its ring 12 located between the head 35 and an adjustable nut 46 having a left-hand threaded engagement with the sleeve portion 28 on the cap 26. The nut 46 is adjustably positioned on the sleeve portion 28 to locate the plunger 33 through the fusing element 10 and spray head 35 in the position shown in Figure 1 of the drawings, wherein the head 34 is firmly engaged with the gasket 40 against the action of the coil spring 41.

When the several parts of the fire extinguisher are in the relative positions thereof shown in Figure 1 of the drawings, the spring 41 is held under compression by the fusing element 10 until the temperature of the ambient atmosphere exceeds the fusing temperature of the metal previously described as securing the sections 15 of the band 13 together. When this takes place one or more of the sections 15 are disconnected from the band and the spring 41 displaces the ring 11 from its position between the spray head 35 and the adjusting nut 46. This releases the spring 41 and permits the latter to move the plunger 33 inwardly at a rapid rate. Inasmuch as the outer ends of the cartridges 24 abut the head 34 on the plunger, it follows that the cartridges are moved inwardly in their respective guides by the plunger 33.

As the cartridges are forced inwardly by the spring 41, the inner ends are punctured by the punches 21 and gas under pressure is discharged into the container 10' through openings 20 in the tubular guides 16'. As pressure builds up in the container 10', the fire extinguishing fluid therein is discharged in the form of a spray through the nozzle 11'.

What I claim as my invention is:

1. A fusing link comprising a band composed of a plurality of arcuate sections connected together in overlapping relationship and separable from each other in the presence of heat, arcuate sections free from connection with each other and housed within the band to provide a ring, and spring means for forcing the ring sections laterally outwardly against adjacent portions of the band.
2. A fusing link comprising a plurality of arcuate sections connected together to form a continuous band and separable from one another in response to a predetermined rise in temperature of the ambient atmosphere, arcuate segments free from connection with each other and arranged in the band to form a ring, and spring means for urging the segments outwardly against adjacent sides of the band with a force sufficient to displace the segments and sections laterally outwardly upon disconnecting one or more of said sections.
3. A fusing link comprising a plurality of arcuate sections cooperating with each other to form a continuous band and connected together by a fusing metal, and spring means acting on

the inner surfaces of the band for forcibly displacing the sections laterally outwardly in response to fusing of said metal.

4. A fusing link comprising a plurality of arcuate sections connected together to form a continuous band and separable from one another in response to a predetermined rise in temperature of the ambient atmosphere, fins projecting radially outwardly from the band to facilitate the conduction of heat from the atmosphere to the sections, and spring means acting on the inner surface of the band for forcibly displacing the sections laterally outwardly in response to separation of the sections.

5. A fusing link comprising a plurality of arcuate sections cooperating with each other to form a continuous band and connected together by a fusing metal, a fin projecting radially outwardly from each section of the band to facilitate the conduction of heat from the atmosphere to the fusing metal connecting the band sections, and spring means within the band for forcibly displacing the sections laterally outwardly in response to fusing of said metal.

6. A fusing link comprising a plurality of arcuate sections arranged in overlapping relationship to form a continuous band and connected together with a fusing metal, arcuate segments free from connection with each other and arranged in the band to form a ring, and spring means housed within said ring and exerting an outward force on the ring segments sufficient to forcibly displace the ring segments and band sections outwardly upon fusing of the metal

holding two or more of the sections together.

7. A fusing link comprising a band composed of a plurality of arcuate sections connected together in overlapping relationship and separable from each other in the presence of heat above a predetermined temperature, a plurality of fins spaced from each other circumferentially the band and extending generally radially outwardly from the band to facilitate the conduction of heat from the atmosphere to said sections, arcuate segments free from connection with each other and housed within the band to provide a ring, and spring means located within the ring for forcing the ring segments laterally outwardly against the inner surface of the band.

8. A fusing link comprising a band composed of a plurality of arcuate sections having the free ends arranged in overlapping relationship and connected together with a fusing metal, and spring means located within the band and acting on said sections to displace the latter laterally outwardly upon fusing of the metal holding the overlapping end portions of the sections together.
